[57] CLAIM

The ornamental design for a coolant wrap, as shown and described.

DESCRIPTION

FIG. 1 is a top plan view of a coolant wrap showing our new design;

FIG. 2 is a front elevational view thereof;

FIG. 3 is a left side elevational view thereof;

FIG. 4 is a right side elevational view thereof;

FIG. 5 is a bottom plan view thereof;

FIG. 6 is a rear elevational view thereof;

FIG. 7 is a front perspective view thereof in use position; and,

FIG. 8 is a rear perspective view thereof in use position;

The broken lines shown around the periphery of the article represent top-stitching. The cross-line pattern which is partially shown for ease of illustration, represents a conventional fabric.

FIG. 1.

FIG. 3.

FIG. 2.

FIG. 5.

FIG. 6.

FIG. 4.

FIG. 7.FIG. 8.
